UNITED STATES PATENT OFFICE.

JOSEPH C. DONNELLY, OF BARBERTON, OHIO, ASSIGNOR TO THE DIAMOND MATCH COMPANY, OF CHICAGO, ILLINOIS, A CORPORATION OF ILLINOIS.

MACHINE FOR PACKING MATCHES.

Application filed December 27, 1923. Serial No. 682,894.

To all whom it may concern:

Be it known that I, JOSEPH C. DONNELLY, a citizen of the United States, and resident of Barberton, in the county of Summit and 5 State of Ohio, have invented certain new and useful Improvements in Machines for Packing Matches, of which the following is a specification.

This invention relates to machines for 10 packing matches in boxes; and more especially to a type of packing machine wherein each box tray is successively supplied with two approximately like quantities of matches having their heads pointing in opposite directions to each other, as illustrated in Letters Patent of the United States No. 1,016,436, dated February 6, 1912, to which reference may be had.

The object of the invention is to effect 20 the uniform settling and straightening of the matches in each succeeding tray after the tray has received its first supply of matches. Accordingly, the invention comprises novel principles, features of construction and combinations of parts, which will be hereinafter described and claimed.

In the drawings—

Figure 1 is a side elevation of a portion 30 of a match packing machine embodying the principle of my invention, only so much of the machine being shown as is necessary to illustrate the improvements.

Fig. 2 is a plan of the mechanism shown in Fig. 1.

Fig. 3 is a vertical section, transversely of 35 the vibratory supply trough, as on the line 3—3 of Fig. 2.

Fig. 4 is a left end view, enlarged, of a 40 part of the mechanism of Fig. 2, showing the settling and straightening devices as positioned upon the contents of the match tray while the succeeding tray is being supplied with matches.

Fig. 5 is a side elevation, partly in section, of the straightening and settling members, including a portion of the vibratory supporting arm therefor.

Fig. 6 is a transverse vertical section 45 through the said members, as on the line 5—6 of Fig. 5.

Fig. 7 is a similar section, as on the line 7—7 of Fig. 5, showing the said members as in action upon the contents of a match tray.

Fig. 8 is a perspective view of the device 55 as mounted on a section of the inclined feed hopper, the pressure member being shown as detached.

Referring to the drawings, 10 designates 60 a part of the bed or table upon which the tray conveyer is supported and guided. This conveyer, in the form illustrated, comprises an endless chain of links 11 provided on their inner sides with gear teeth 12 with which mesh the teeth of actuating gear wheels 13, and on their upper sides with vertically movable holders 14 for the box trays 15.

16 designates a portion of an inclined 70 match supply trough having adjacent its lower end two spaced-apart discharge openings 17, 18 located above the paths of the trays in the conveyer, which trough is rapidly reciprocated lengthwise in a manner to feed the matches to the openings. These 75 openings are respectively equipped with sliding gates 19 which are actuated at intervals to cut off the delivery of matches from the trough.

20 designates a pair of vertically-recipro- 80 cative channelled brackets adjacent the first discharge opening 17 of the supply trough. These brackets are designed to receive the ends of the bottom plate of each succeeding 85 holder 14 when the contained tray therein is beneath the first discharge opening, so that when the brackets are raised and lowered in respect to such opening the holder and its tray are likewise actuated. The 90 brackets are supported by a rising and falling yoke frame 21 under the control of an appropriate cam 22 on a driven shaft of the machine.

When the tray is raised the gate of the 95 opening 17 is retracted and a charge of matches is thus delivered to the tray from the trough. The gate is then moved to close the opening, and the tray is lowered. The conveyer is then advanced to remove the tray-holder with its partially filled tray from the brackets, and at the same time a succeeding tray holder, with a tray therein, is engaged by the channelled brackets preparatory to the vertical movement thereof, and so on; all as set forth in Patent No. 1,016,436 aforesaid.

Preferably the lower portion of the trough is jointed to a bracket 22' on the bed by

means of a vertical link 23, instead of slidably supporting such portion upon a stationary bracket as in the previous construction.

- 5 My invention comprises means for uniformly settling and leveling the first charge of matches in each succeeding tray, in order that the interior of the tray shall be in proper condition to receive the second 70 charge of oppositely-positioned matches. 10 Such means, in its preferred form, is as follows:

To a side of the lower portion of the trough, is pivoted, as at 24, one end of a 15 relatively heavy arm 25, the other or free end of which is positioned to overhang the interior of the tray when the latter is advanced beyond the first charging opening. This arm not only partakes of the compound vibratory motion of the trough, but it also has capacity for independent vertical movement on its pivotal support. The free end of the arm is provided with a depending foot 26 to the under side of which is 25 secured a metal block 27 constituting a head that, by actuation of the arm, is movable into and from the interior of the underlying tray. The underside of the head is inclined correspondingly with the top of the charge of matches in the tray, so as to bear uniformly upon the contained matches when the head is lowered into the tray. Such inclined surface is preferably scalloped or serrated transversely thereof, as at 28, so 30 as to engage the opposing matches, and its ends are upwardly beveled or inclined, as at 29, so as to ride smoothly on the matches. The long sides of the head have preferably affixed thereto plates 30, of fibre or other frictional material, the lower edges of 35 which are grooved or scalloped to coincide with the bottom formation of the head and similarly rest upon the matches. The ends of the head extend beyond the adjacent end 40 of the foot, as at 31, and afford seats upon which loosely rest the respective ends of an open rectangular metal frame 32 having parallel side walls 33 which embrace the head and depend normally below the serrated face of the latter. These walls, when 45 the head is lowered into the underlying tray, bear yieldingly upon, and accommodate themselves at once to the inclination of the upper matches contained in the tray. (See 50 Fig. 7.)

On the outer end of the arm 25 is a roll 55 34 which rests on a toe 35 formed on one arm 36 of a rock-lever that is fulcrumed at 37 on a suitably disposed bracket 38 on the bed. The other arm 39 of the lever is slotted, as at 40, to receive a wrist-block 41 pivoted on the adjacent side of one of the brackets 20. Hence during the upward and 60 downward movement of the bracket the lever is rocked in a manner to lower and 65

raise the toe 35 upon which the roll 34 is supported. In the downward movement of the toe the acting end of the arm 25, together with the head 27 and the frame 32, descends by gravity, and such head and frame are positioned within the underlying tray; and in the upward movement of the toe it positively raises the arm 25 and lifts the head and frame well above the top of the tray.

From the foregoing it will be seen that 75 when one tray is in its raised position beneath the opening 17 and receiving a charge 80 of matches from the trough, the previously charged tray is in down position and its contents are being acted upon by the vibrating head and its associated pressure frame, which together rest by gravity upon the contained matches and therefore exert a downward pressure as well as a reciprocatory action upon the matches. During the 85 motion of the head the transverse serrations thereof act upon the matches to distribute them uniformly within the tray, and the independent yielding pressure of the walls of the frame upon the matches, adjacent 90 their respective ends, contribute to the efficient leveling and settling of the matches within the tray, so that when the tray is subsequently presented to the second discharge opening of the trough the contents 95 of the tray are uniformly settled and leveled and the interior of the tray is in proper condition to receive the second charge of matches, as previously mentioned.

A pair of spaced-apart Z-strips 41, which 100 are fastened on the bed in position to receive and embrace each succeeding tray holder when it is advanced beneath the vibratory head and frame, firmly maintain the said holder and its tray in place when 105 the matches within the tray are being acted upon by the head and frame.

It is to be understood that my invention is not limited to the particular construction herein disclosed, as the mechanism may be 110 modified within the principle of the invention and the scope of the appended claims.

I claim—

1. In a machine for packing matches, the combination of a longitudinally reciprocable supply trough having a discharge opening therein, a conveyer for feeding a succession of match receptacles in a path under and past said opening, a vertically-movable arm pivotally connected with said trough, a 115 match settling and straightening device carried by said arm so as to overhang the path of each receptacle when it has passed beyond the opening, said device comprising a head having a serrated inclined lower surface 120 and upwardly beveled ends, and means for permitting said head to gravitate into and for raising it from the interior of the receptacle.

2. In a machine for packing matches, the 130

combination of a longitudinally recipro-
5 cal supply trough having a discharge open-
ing therein, a conveyer for feeding a suc-
cession of match receptacles in a path under-
10 and past said opening, a vertically-movable
arm pivotally connected with said trough,
a settling and straightening device carried
by said arm so as to overhang the path of
each receptacle when it has passed beyond
15 the opening, said device comprising a head
fast on the arm and a pressure member
loosely supported in relation to the head
and having spaced apart depending por-
tions which embrace the head and rest upon
20 and automatically accommodate themselves
to the inclination of the match contents of
the receptacle, and means for permitting
said head and member to gravitate into, and
for raising them from the interior of the
25 receptacle.

3. In a machine for packing matches, the
combination of a longitudinally recipro-
5 cal supply trough having a discharge open-
ing therein, a conveyer for feeding a suc-
cession of match receptacles in a path under-
10 and past said opening, a vertically-movable
arm pivotally connected with said trough,
a serrated head fast on said arm, and a pressure
frame loosely supported in
15 relation to the head and having spaced de-
pending walls embracing the head to auto-
matically position themselves upon the in-
clined matches within the receptacle, and
means for permitting said head and frame
20 to gravitate into, and for raising them from
the interior of the receptacle.

4. In a machine for packing matches in
a succession of receptacles, match settling
and straightening mechanism overhanging
40 the path of said receptacles and comprising
a vertically movable arm, means for pivot-
ally supporting and longitudinally vibrat-
ing said arm, a head fast on said arm and
having a serrated inclined lower surface
45 and upwardly beveled ends, and means for
permitting said head to gravitate into, and
for raising it from the interior of an un-
derlying receptacle.

5. In a machine for packing matches in
a succession of receptacles, match settling
and straightening mechanism overhanging
50 the path of said receptacles and comprising
a vertically-movable arm, means for pivot-
ally supporting and longitudinally vibrat-
ing said arm, a serrated head fast on
said arm, a pressure member embracing said
55 head and loosely supported in relation thereto,
said member having spaced-apart
depending portions which embrace the head
and rest upon and automatically accommo-
date themselves to the inclination of the
60 match contents of the receptacle, and means
for permitting said head and member to

gravitate into, and for raising them from
the interior of an underlying receptacle. 65

6. In a machine for packing matches, the
combination of a longitudinally recipro-
5 cal supply trough having a discharge open-
ing therein, a conveyer for feeding a suc-
cession of match receptacles in a path under-
10 and past said discharge opening, means for
raising and lowering succeeding
receptacles beneath the opening, a verti-
cally-movable arm pivotally connected with
15 said trough, a settling and straightening
head carried by said arm so as to overhang
the path of each receptacle when it has
passed beyond the opening, and means for
permitting said head to gravitate into, and
20 for raising it from the interior of the re-
ceptacle, said last-named means being actuated
by the means for raising and lower-
ing the receptacles. 25

7. In a machine for packing matches, the
combination of a longitudinally recipro-
5 cal supply trough having a discharge open-
ing therein, a conveyer for feeding a suc-
cession of match receptacles in a path under-
10 and past said opening, means, includ-
ing a vertically-movable frame, for raising
and lowering succeeding receptacles be-
neath the opening, a vertically movable arm
15 pivotally connected with said trough, a
match settling and straightening head car-
ried by said arm so as to overhang the path
of each receptacle when it has passed be-
yond the opening, and means, including a
20 rock-lever connected with and actuated
by said frame, for permitting said head to
gravitate into, and for raising it from the
interior of the underlying receptacle. 25

8. In a machine for packing matches, the
combination of a longitudinally recipro-
5 cal supply trough having a discharge open-
ing therein, a conveyer for feeding a suc-
cession of match receptacles in a path under-
10 and past said opening, means, includ-
ing a vertically-movable frame, for raising
and lowering succeeding receptacles beneath
the opening, a vertically-movable arm piv-
15 otally connected with said trough, a match
settling and straightening head carried by
said arm so as to overhang the path of each
receptacle when it has passed beyond the
opening, a pressure member embracing said
115 head and loosely supported in relation thereto,
and means, including a rock-lever con-
nected with and actuated by said frame, for
permitting said head and member to gravi-
tate into, and for raising them from the in-
120 terior of the underlying receptacle.

Signed at Barberton, in the county of
Summit and State of Ohio, this 24th day of
December, A. D. 1923.

JOSEPH C. DONNELLY.
